Francis Wingate of Hallowell, Maine
Sister's Patent.

The Schedule is as follows Letter Patent and making part of the same containing a description in the words of the said Francis Wingate himself of his improvement being a mode of protecting and covering hay and grain from the weather.

It is known that Francis Wingate of Hallowell in the County of Kennebeck and State of Maine have invented a new and useful improvement in the covering for preserving hay and grain, and securing them from the weather, and the following is a full and exact description of the construction and operation of the said covering as invented or improved by me. The covering is to be of cotton, tow, or other cloth to be covered with oil and paint on top and the composition does to entirely shed water. The dimensions of the covering will be governed by the quantity to be covered, varying according to the size of the stack, rack or shock and it may be round or square. It takes lines and loops at the edges, the lines, to be fastened to pegs prepared to secure the covering by thrusting the pegs into the hay or grain to keep it close that it may shed water. What I claim as new and as my own improvement is the application of the above described covering to the preservation of hay and grain in stacks, in racks, & shocks.
